(57) **CLAIM**

The ornamental design for an electronic ballast, as shown and described.

DESCRIPTION

FIG. 1 is a perspective view of the electronic ballast showing my new design;

FIG. 2 is a left view thereof.

FIG. 3 is a right view thereof.

FIG. 4 is a top view thereof.

FIG. 5 is a bottom view thereof.

FIG. 6 is a front view thereof; and,

FIG. 7 is a rear view thereof.

The broken lines in the drawings illustrate portions of the electronic ballast which form no part of the claimed design.
